R. D. TAPLING

EXERCISING DEVICE

Filed Feb. 25, 1922

4 Robert D. Tapling

INVENTOR

BY Victor J. Evans

ATTORNEY

UNITED STATES PATENT OFFICE.

ROBERT D. TAPLING, OF CHICAGO, ILLINOIS.

EXERCISING DEVICE.

Application filed February 25, 1922. Serial No. 539,194.

To all whom it may concern:

Be it known that I, ROBERT D. TAPLING, a citizen of the United States, residing at Chicago, in the county of Cook and State of Illinois, have invented new and useful Improvements in Exercising Devices, of which the following is a specification.

This invention relates to exercising devices and more particularly to a device in the 10 shape of a spring shoe. The main object of the invention is to provide a novel form of device of this character which when used in connection with a novel form of spring staff will enable the wearer to make leaps or jumps 15 of comparatively great length with ease, enabling him to get over the ground quickly and with minimum exertion.

Another object of this invention is to provide an exercising device as specified which 20 comprises an attaching plate having an arcuate flat spring attached thereto, and designed to yieldably support the wearer, the spring being tensioned in proportion to the weight of the person by which they are to 25 be worn.

A further object of this invention is to provide a staff to be used in connection with the improved exercising device which has a yieldable ground engaging portion formed 30 of springs which when used in connection with the improved exercising device will enable the wearer to spring and jump over the ground much in a manner in which a kangaroo travels.

35 Other objects of the invention will appear in the following detailed description taken in connection with the accompanying drawing wherein:

Fig. 1 is a view illustrating the use of the 40 improved shoe and staff.

Fig. 2 is a perspective view of the spring shoe.

Fig. 3 is a detail section on the line 3—3 of Fig. 2.

45 Fig. 4 is a detail section on the line 4—4 of Fig. 2.

Referring more particularly to the drawings, the improved spring shoe exercising device comprise the sole plate 1 which may be 50 attached in any suitable manner to the shoe soles of the wearer. The runner or supporting portion of the improved shoe is formed of a single strip of flat spring steel as shown at 2 and it has one end attached to the under surfaces of the toe end of the

sole 1 as shown at 3 in Fig. 2 of the drawings. The strip of spring steel 2 curves forwardly and downwardly from the attaching point 3 and is sinuously curved providing a large bowed portion at the rear end of the 60 shoe which extends above the sole 1 and curved downwardly to the sole in a relatively short curve 4. From the relatively short curve 4 the strip 2 of spring steel extends through a strap 5 as clearly shown in Fig. 3 65 of the drawings, which strap is riveted or otherwise suitably attached to the under surfaces of the sole 1. From the strap 5, the strip of spring steel curves forwardly and downwardly and it has its end remote from 70 the attached forward end connected to the strip, intermediate the front curved portion 6 and the rear relatively large curved portion 7 which terminates in a short curve. The terminal 8 of the strip of resilient steel 75 is bent forwardly to lie above the upper surfaces of the strip and is attached thereto by a bolt 9 which bolt has clamping nuts 10 mounted thereon between the end 8 and the strip 2 to permit adjustment of the relative 80 positions of the terminal 8 and the adjacent portion of the strip. The bolt 9 has a lateral extension 11 formed thereon which is bent to provide a substantially U shaped portion 12 engaging over the edge of the terminal 8 85 as clearly shown in Fig. 4 of the drawings.

A staff structure 20 is provided for use in connection with the improved type of shoe just described, and this staff structure comprises a handle 21 which has a tail 22 attached to one end thereof. The tail 22 is formed of flat spring steel similar to that of which the runner 2 of the shoe is formed and it is bent to provide a loop 23, as clearly shown in Fig. 1 of the drawings having a 90 convex surface or side to be presented for engagement with the ground. The loop 23 of the tail 22 is reinforced by springs 24 and 25 which are attached to the loop or the handle 21 and extend across the loop for bracing the loop and increasing the spring action thereof. In use, the staff 20 is placed between the legs of the user as shown in Fig. 1 of the drawings and used to assist in impelling him forwardly and also as an aid in 105 proper landing after the completing of a jump.

It is, of course, to be understood that the invention may be constructed in other manners and the parts associated in other rela- 110

tions and, therefore, I do not desire to be limited in any manner except as set forth in the claims hereunto appended.

Having thus described my invention what

5 I claim is:

10 1. A spring shoe exercising device comprising a sole plate, a spring runner having one end connected to the toe end of the sole plate, and means slidably connecting said

runner to the sole plate at the heel thereof.

15 2. A spring shoe exercising device comprising a sole plate, a spring runner having one end connected to the toe end of the sole plate, means slidably connecting said runner to the sole plate at the heel thereof, said runner extended downwardly from its slidable connection with the heel plate and having its end rigidly connected to the runner intermediate its front and rearward portions.

20 3. As a new article of manufacture, a spring shoe exercising device comprising a sole plate, a runner formed of a single strip of flat spring material having one end attached to the toe end of the sole plate, said

runner curving sinuously from its attached end, a strap attached to the under surfaces of the sole plate adjacent its heel, said strip of spring material extending through said strap for slidably connecting the runner to the rear end of the sole plate.

30 4. As a new article of manufacture, a spring shoe exercising device comprising a sole plate, a runner formed of a single strip of flat spring material having one end attached to the toe end of the sole plate, said runner curving sinuously from its attached end, a strap attached to the under surfaces of the sole plate adjacent its heel, said strip of spring material extending through said strap for slidably connecting the runner to the rear end of the sole plate, said strip of spring material extending forwardly and curving downwardly from said strap and having its terminal attached to the strip intermediate the front and rearmost curved portions.

35 In testimony whereof I affix my signature.
40 ROBERT D. TAPLING.
